MISSOURI, A CORPORATION OF MISSOURI.

THREAD-CONTROLLING MECHANISM FOR SEWING-MACHINES.

1,134,035.

Specification of Letters Patent. Patented Mar. 30, 1915.

Application filed July 11, 1911. Serial No. 638,024.

To all whom it may concern:

Be it known that we, GEORGE L. CORCORAN, GEORGE A. DOBYNE, and AUGUST R. SCHOENKY, citizens of the United States, residing at St. Louis, in the State of Missouri, have invented a new and useful Thread-Controlling Mechanism for Sewing-Machines, of which the following is a specification.

10 This invention relates to sewing machines and particularly to thread controlling means therefor.

One of the objects of this invention is to construct a thread controlling mechanism which will positively and uniformly set the stitches irrespective of the thickness of the work, and which will accurately measure off thread from the supply for the different stitches, the amount of measured thread being varied and controlled automatically in accordance with the thickness of the work.

Another object is to provide a novel and positive lock which is simple in construction, consists of a few parts, and is easily assembled and disassembled.

Another object is to construct a thread controlling mechanism in which the functions of certain of its elements are combined so as to work together and be operated from a common actuator; and to make the controlling connection to the work engaging member a simple and direct connection, thereby reducing the number of parts and providing a simple construction which is not liable to get out of repair.

Further objects will appear from the detail description taken in connection with the accompanying drawings in which:

Figure 1 is a side elevation of a sewing machine embodying this invention, Fig. 2 is a detail side elevation from the other side of the machine showing the thread controlling mechanism, Fig. 3 is a detail plan of the mechanism shown in Fig. 2, Fig. 4 is a detail side elevation of the thread controlling mechanism from the same side of the machine as Fig. 1, Fig. 5 shows in perspective details of the thread-lock, and Fig. 6 is a side elevation from the opposite side of the machine from that shown in Fig. 1.

The machine to which this invention is applied may be such as is shown and de-

scribed in application Serial No. 631,290. In said application the thread controlling mechanism is shown combined with the elements of the stitch forming mechanism and accessory parts, and the same parts are herein designated by the same reference characters as in said application.

The machine to which this invention is shown as applied is an outsole stitcher, although it may be applied to other types of machines.

In the accompanying drawings, 25 designates a column upon which is mounted a head or base 26 having formed thereon a lug 27 provided with bearings for a shaft 28 which supports a series of actuating levers as described in said application. A pair of 70 brackets 29 are bolted to the head and provided with bearings for a main drive shaft 30 which supports three cam wheels, one of which is shown at A and the other at C, and the third wheel (not shown) is supported 75 between these two as described in said application. The right-hand bracket looking from the front of the machine has formed thereon a forwardly extending lug 31 to provide a bearing for the take-up actuating 80 lever. The head 26 has cast integral therewith a lug 32 forming bearings for various mechanisms. A casting 35 is bolted to the lug 32 and supports the shuttle race 39 and its shuttle. A bracket 40 is bolted to the 85 head 26 and is provided with an arm 42 forming a bearing for the take-up shaft.

The curved hook needle is shown at 52, the thread lifter at 70, the thread holder at 80, and the looper at 82. The feed slide 90 101 is supported in its guideway 100 and supports the curved awl 103.

The above mechanisms are fully described in said application to which reference is had.

A work support 129 is mounted upon the casting 35 and is provided with an oblong slot for the awl and needle, as is common in machines of this type, and with a lug 130 forming a gage for the edge of the sole. 100 The presser-foot 131 is pivotally mounted upon the shaft 79 supported between the lug 32 and a bracket 77 on 32, and this presser-foot has a rearwardly extending arm 132 rigidly connected thereto. An arm 133 is 105 loosely mounted upon the shaft 79 and is

yieldingly connected to the arm 132 by means of a link 134, a spring 135 and an adjusting nut. The arm 133 is provided with a rack or ratchet 136 adapted to be engaged by a pawl or dog 137 mounted upon an actuating lever 138 pivoted at its rear end on the head 26. A spring 139 bears on the dog and throws it into engagement with the rack and the actuating lever is provided with a cam roll 140 engaging a cam groove in one of the cam wheels. The arm 132 is also provided with a rack 141 adapted to be engaged by a dog 142 which is held in engagement therewith by means of a spring 143. A fixed pin 144 on the lug 32 is adapted to be engaged by the dog 137 so as to throw it out of engagement with the rack 136 when the actuating lever 138 is moved to its lowered position. The lever 138 is provided with a heel 145 adapted to engage the tail-piece 146 on the dog 142 to throw it out of engagement with the rack 141. In this way both dogs are thrown out of engagement with their racks when the actuating lever is moved to lowered position by its cam. A link 148 connects the arm 132 with an arm 149 on a shaft 150, and a comparatively light spring 151 bearing at one end on the guideway 100 and at its other end against the lower face of the arm 149 tends to rotate the shaft 150 clockwise, and thus the spring acting through the linkage connection 148 with the arm 132 holds the presser-foot with a light pressure on the work. A link or rod 147 connects the arm 132 with a treadle (not shown) so that the presser-foot may be raised manually. In the operation of this presser-foot mechanism as fully described in said application, the presser-foot is held on the work under increased pressure of the spring 135 and is locked in position. During the feeding operation however the presser-foot is unlocked and the increased pressure released so that the presser-foot will be only under the tension of the light spring 151 during such feeding operation. At the completion of the stitch the presser-foot is also unlocked and released so that it may be raised at this time. This is fully described in the application referred to. It will be seen that the presser-foot will automatically accommodate itself to the thickness of the work on the work support, and that it will positively position the shaft 150 through the lever and link connections 149, 148, 132.

The thread controlling mechanism consists of a take-up member and a coöperating thread-lock. The take-up member has a two-fold function, namely to take up and set the stitch, and to draw thread from the supply. The thread-lock is arranged to lock or clamp the thread while the take-up member operates to take up the thread and set the stitch, and the thread-lock opens thereafter during

the latter part of the movement of the take-up member to permit said member to draw thread from the source of supply.

The shaft 150 extends through the lug 32 and has keyed thereto one of the clamping members or elements 160 of the thread-lock. The coöperating clamping member or element 161 of the thread-lock is loosely mounted upon the shaft 150 so as to be capable of angular displacement with respect to the member 160, and is provided with a pin or roll 162 adapted to be engaged by a toe on the take-up member as hereinafter described. The lock member 160 is provided with a cam groove or incline 163 extending across its face and the lock member 161 is provided with cam projections 164 adapted to coöperate with the groove 163. The projections 164 consist of steel balls loosely mounted in substantially semi-spherical cavities in the member 161, the cavities being slightly deeper than the radii of the balls, and the edges of the cavities being peened over to hold the balls loosely in place. The inside face of the member 161 is beveled at 165 adjacent to shaft 150 so as to prevent binding or cutting of the thread. The members 160 and 161 are placed in coöperative relation on the shaft 150 with the balls 164 in the groove 163, and a spring 166 bearing at one end against the member 161 and at the other end against a nut 167 is arranged to hold the members in yielding engagement. The tension of the spring may be adjusted by means of the nut 167 which is provided with a lock nut 168. The groove 163 has its edges beveled and rounded as shown in Fig. 5 so as to permit the balls to ride easily on the cam portion. If one of the lock or clamp members is rotated with relation to the other, the balls will ride up on the inclined faces of the cam groove so as to separate the thread engaging faces a distance depending upon the angular displacement of these lock members. If the lock members are freed, the spring 166 will tend to move the balls down the inclines of the cam groove to their lowest position, and thus throw the lock members together. The cam groove is of such a depth that when the balls are in position therein, the locking member faces will be in clamping engagement to clamp the thread. It will thus be seen that a rotation or angular movement of the lock member 161 on the shaft 150 will move the lock member 161 away from the lock member 162 against the tension of the spring 166, and that the spring will return them into engagement. The relative rotation of the members is of course never enough to move the balls entirely out of the groove.

A take-up shaft 169 is supported in bearings in the lug 32 and in a bracket on the right side of the machine. This shaft 169

has secured thereto an arm 170 which is connected by a link 171 with an arm 172 of an actuator lever mounted upon a shaft 173 in the lug 31. The other arm 174 of this lever 5 is provided with a cam roll 175 engaging the cam groove c^2 in the cam wheel C. An arm 176 is rigidly secured to the take-up shaft 169 to move therewith, and a take-up arm or member 177 provided at its end with a 10 thread roll or pulley 178 is loosely mounted on the take-up shaft. A threaded link 179 is pivotally connected at one end to the arm 176 and passes through a trunnion member 180 pivotally connected to the take-up arm 15 at 181. The link passes loosely through the trunnion member and is provided with nuts 182 arranged to adjustably connect the link with the trunnion member and lock it in position after it is adjusted. The take-up 20 arm 177 is provided with a toe 183 which is adapted to engage the roll 162 on the lock member 161. The thread t passes from the source of supply through a suitable tension device (not shown), through the wax pot, 25 (not shown) through a tube 184, between the lock members, over a loose guide pulley 185, over the pulley 178 on the take-up arm, through the eye in the looper, and through the slot in the work support 129. The pulley 30 185 is provided with a bridge 185^a (Fig. 3) to hold the thread in place.

The operation of the thread controlling mechanism is as follows: After a loop of thread is on the shuttle and ready to be discharged therefrom, the take-up cam groove c^2 will through its connections operate the take-up arm 177 so as to move it down and take up the thread. At the beginning of the take-up movement the take-up arm will be 35 in the dotted position Fig. 4, and the toe 183 will be out of engagement with the roll 162 so that the spring 166 will clamp the lock members together to firmly lock or clamp the thread. The thread will thus be clamped 40 at a point between the take-up arm and the source of supply, and will remain clamped or locked while the take-up arm takes up the thread and also while it sets the stitch. Near the limit of the stroke of the take-up 45 arm, and after the stitch has been set, the toe 183 will engage the roll 162 and further movement of the take-up arm will cause the toe to rotate the lock member 161 counter-clockwise and spread the lock members apart 50 in the manner hereinbefore described so as to release or unclamp the thread. The thread being thus released, the take-up arm will operate during the last part of its stroke to draw or measure thread for the next 55 stitch from the source of supply. At the limit of the stroke of the take-up arm (shown in full lines in the drawings) the thread-lock will be fully opened. It will therefore be seen that during the downward 60 movement or stroke of the take-up lever, 65

which may for convenience be termed the "take-up stroke", this take-up lever performs two functions: In the first part of its movement it will take up and set the stitch, and thereafter this lever will act as a pull-off 70 to draw or measure from the supply an amount of thread sufficient to form the next stitch. The opening of the thread-lock determines the end of the take-up action and the beginning of the thread drawing action 75 of the take-up lever. As the take-up arm starts to move back, the toe will in the first part of its movement move out of engagement with the roll on the lock member and thus the spring 166 will operate to move this 80 lock member 160 back in position to clamp the thread. In referring to the shape of the cam groove c^2 Fig. 1, it will be seen that the take-up arm moved in steps is given two preliminary movements during the first part 85 of the cycle of operations of forming a stitch. The first movement is for the purpose of releasing the locking member 161 so as to clamp the thread and for the purpose of relieving the tension of the thread, and 90 the purpose of the second movement is to give up thread to the looper. The third or final movement is the one in which the thread is given up to the shuttle. It will thus be seen that the take-up arm performs the 95 double function of taking up and setting the stitch, and of drawing or measuring thread from the source of supply. Different thicknesses of stock however require different amounts of measured thread, and means 100 must be provided for varying the amount of measured thread in accordance with the thickness of the stock. This is accomplished as follows: It will be noted that the take-up arm engages the roll 162 in the latter part 105 of its stroke, and that the take-up arm moves through a fixed arc and to a fixed limit during its take-up and thread drawing stroke. It will therefore be seen that if the take-up member could be made to engage the roll 110 earlier or later in its stroke it would open the lock earlier or later and thus the thread drawing movement of the take-up arm could be increased or decreased. This can be accomplished by moving the take-up engaging portion of the lock with respect to the take-up arm. The shaft 150 and the lock member 160 keyed thereto are connected to the presser-foot through the lever and link connections 149, 148, 132. Since the work support 129 is rigid, the movable work engaging member or presser-foot 131 will vary in its position in accordance with the thickness of the work, and thus the lock member 160 connected to the presser-foot 115 will vary in its position in accordance with the thickness of the work. Since the lock member 161 is normally connected to and movable with the lock member 160, this lock member and the roll 162 connected there- 120 125 130 135

with will vary in position with respect to the toe 183 in accordance with the thickness of the work. Thus as the thickness of the work increases the shaft 150 and the roll 162 movable therewith will be moved in a clockwise direction so as to move the roll 162 to the left Figs. 1 and 4, toward the toe 183. In this way the roll 162 will be engaged by the toe 183 earlier in the movement of the take-up arm so that the thread-lock will be opened earlier and thus the thread drawing movement of the take-up arm will be increased. A decrease in the thickness of the stock will have the reverse effect.

15 There is a direct and positive connection between the presser-foot and the thread-lock so that the thread-lock will be positively adjusted bodily with respect to its actuator in order to vary the point of engagement and therefore the point at which the lock is opened. This direct connection together with the combining of the functions of the different elements of the thread controlling mechanism not only simplify the construction, but also result in a reduction of operating expense and facilitates renewal of parts. The lock members are so arranged that the lock may be easily taken apart for cleaning purposes which is necessary in wax thread sewing machines. Thus in order to disassemble the lock, it is only necessary to move the take-up lever to dotted position Fig. 4 which will throw the toe out of the path of the lock or clamping member 161 when this member can be easily slipped off of the shaft by removing the nuts 167 and 168. It will therefore be seen that in accordance with this invention the thread is measured automatically in accordance with the thickness of the work so that the lock will be drawn a uniform distance from the surface of the work, irrespective of its thickness. This is accomplished by varying the thread drawing action of the take-up mechanism, and by giving the thread-lock a variable action so as to release the thread at a variable point. In order to adjust the mechanism independent of its automatic means, such for instance as for preliminary adjustments or for different lengths of stitches, the take-up arm 177 can be adjusted by lengthening and shortening the link 179, thereby independently adjusting the take-up arm with respect to the thread-lock.

55 The machine is provided with stopping mechanism for stopping it in a predetermined position. Such mechanism has been fully described in the application referred to. This stopping mechanism may consist of an ordinary clutch, in which case the machine is provided with positioning means comprising a pointer 201 on the frame and a mark 202 on the cam wheel C, the machine being provided with the usual hand wheel 65 for turning it over. The machine may also

be provided with automatic stopping mechanism for automatically arresting it in a predetermined position. The instrumentalities together with their actuators are so constructed and arranged and timed that at 70 the completion of the stitch these instrumentalities are in a position to permit removal of the work at the completion of the stitch. At the completion of the stitch the awl and needle will be out of the work, the presser-foot will be unlocked, and the take-up arm will be at the limit of its downward stroke, so that the lock will at this time be open so as to release the thread. The stopping mechanism is arranged to stop the machine 80 at this time or at the completion of the stitch. The work can therefore be removed at the completion of the stitch, and since the presser-foot is unlocked at this time the raising of the presser-foot will further open 85 the lock so as to completely release the thread. This has been fully described in the application referred to.

It is obvious that various changes may be made in the details of construction without departing from this invention, and it is therefore to be understood that this invention is not to be limited to the specific construction shown and described.

Having thus described the invention what 95 is claimed is:

1. In a sewing machine, the combination of a member constructed to take up and set the stitch and draw thread from the supply, a thread-lock separate from said member, an actuating connection between said member and thread-lock constructed to cause said member to actuate said thread-lock and release the thread during the take-up stroke of said member, and means for 100 operating said member and thread-lock, said means being constructed to cause said member to take up and set the stitch and draw thread from the supply.

2. In a sewing machine, the combination 110 of a thread-lock, an actuator therefor, a take-up member connected with said actuator, means for moving said actuator to engage and open said thread-lock during the take-up stroke of said take-up member, and means for relatively adjusting said thread-lock and actuator automatically in accordance with the thickness of the work constructed to cause said actuator and thread-lock to engage earlier or later during the 120 stroke of the take-up member.

3. In a sewing machine, the combination 125 of thread engaging means having a rotatively supported actuated member, an actuator adapted to actuate said actuated member, and a work engaging member connected to adjust said actuated member rotatively to vary the operation of said actuator on said actuated member.

4. In a sewing machine, the combination 130

- of thread engaging means having a rotatively supported actuated member, an actuator adapted to engage and actuate said actuated member, and a work engaging member connected to adjust said actuated member rotatively to vary the point of engagement of said actuator and said actuated member during the movement of said actuator.
5. In a sewing machine, the combination of thread engaging means having an actuated member, a rotatable shaft for supporting said actuated member, an actuator, a rotatable shaft for said actuator positioned parallel with said first shaft, and a work engaging member connected to adjust said first shaft rotatively to vary the operation of said actuator on said actuated member.
10. 6. In a sewing machine, the combination of a thread-lock, a supporting shaft therefor, a take-up lever having means thereon to operate said thread-lock, and a work engaging member connected to adjust said shaft rotatively to vary the operation of said take-up lever on said thread-lock.
15. 7. In a sewing machine, the combination of thread measuring means including a thread engaging member, an actuator, means for moving said actuator to engage a part of and actuate said thread engaging member, a work engaging member for adjusting said thread engaging member to move said engaged part thereof toward and from said actuator, and means for adjusting said actuator toward and from said engaged part of said thread engaging member.
20. 8. In a sewing machine, the combination of thread measuring means including a thread engaging member, an actuator movable to engage a part of and actuate said thread engaging member, means for automatically adjusting said thread engaging member to move said engaged part thereof toward and from said actuator in accordance with the thickness of the work, and means for manually adjusting said actuator toward and from said engaged part of said thread engaging member.
25. 9. In a sewing machine, thread measuring mechanism including in combination, a thread lock, a stitch setting take-up separate from said thread-lock constructed and operated to draw from the supply and through said thread-lock an amount of thread sufficient to form the next stitch, an actuator for said thread lock, and means for automatically adjusting said thread lock to move a part thereof toward and from said actuator, constructed to vary the thread locking action of said thread-lock in accordance with the thickness of the work.
30. 10. In a sewing machine, the combination of means for locking the thread against movement, a stitch setting take-up member having a thread engaging part and having a part
- thereon adapted to engage and actuate said thread locking means during the take-up stroke to release the thread, and means for operating said take-up member to cause said take-up member to take up and set the stitch and to actuate said thread locking means.
35. 11. In a sewing machine, a thread-lock comprising a pair of relatively rotative thread clamping members, an actuator having a connection with one of said clamping members to rotate it with respect to the other clamping member, and a work engaging member having a connection with the other clamping member.
40. 12. In a sewing machine, a thread-lock comprising a pair of relatively rotative thread clamping members, an actuator having a connection with one of said clamping members to rotate it with respect to the other clamping member, a carrier for said clamping members, and a work engaging member having a connection with said carrier.
45. 13. In a sewing machine, a thread-lock comprising a pair of relative rotative thread clamping members having their co-operating thread clamping faces provided with co-operating cam portions constructed to cause axial separation of said clamping members when said members are relatively rotated.
50. 14. In a sewing machine, a thread-lock comprising a pair of relatively rotative clamping members having means whereby a relative rotation of said members will cause an axial separation, an actuator constructed to relatively rotate said clamping members, a rotatable shaft for supporting said members, and means for moving said shaft rotatively with respect to said actuator.
55. 15. In a sewing machine, a thread-lock comprising a pair of relatively movable thread clamping members, the thread clamping face of one of said members being provided with an incline and the thread clamping face of the other with an antifriction roller movably retained therein and co-operating with said incline.
60. 16. In a sewing machine, a thread-lock comprising a pair of relatively movable thread clamping members, one of said members being provided with an incline and the other with a roller movable therewith and co-operating with said incline.
65. 17. In a sewing machine, a thread-lock comprising a rotatable shaft, a pair of clamping members one rotatable with and the other rotatable on said shaft, and an actuator for rotating the second clamping member.
70. 18. In a sewing machine, a thread-lock comprising a shaft, a pair of clamping members one movable with and the other movable on said shaft, an actuator for the second clamping member, and a work engaging member connected to said shaft.
75. 19. In a sewing machine, a thread-lock

comprising a shaft, a pair of clamping members mounted on said shaft, one of said clamping members being fixed to said shaft and the other member being rotatable on said shaft, an actuator for said rotatable clamping member, and means for rotating said shaft.

20. In a sewing machine, a thread-lock comprising a pair of relatively rotative 10 thread clamping members, a pin on one of said clamping members, an actuator movable to engage said pin and relatively rotate the clamping members, and means for adjusting said pin relatively to said actuator.

21. In a sewing machine, a thread-lock comprising a shaft, a pair of clamping members one movable with and the other rotatable on said shaft, a pin on the rotatable 20 member, an actuator adapted to engage said pin and rotate the clamping member, and a work engaging member connected to said shaft.

22. In a sewing machine, the combination 25 of a stitch setting take-up member having a thread engaging part, a thread-lock separate from said take-up member comprising a pair of thread clamping members, and means operating through said take-up member to separate said clamping members near the end of the take-up stroke of said take-up member.

23. In a sewing machine, the combination 30 of a take-up member having a thread engaging part, a thread-lock comprising a pair of thread clamping members, a work engaging member having a connection with one of said thread clamping members, and means for operating said take-up member 35 and for moving said thread clamping members relatively constructed to separate said

thread clamping members near the end of the take-up stroke of said take-up member.

24. In a sewing machine, the combination 45 of a take-up member having a thread engaging part, a thread-lock comprising a pair of thread clamping members, a carrier for said thread clamping members, a work engaging member having a connection with said carrier, and means for operating said 50 take-up member and for moving said thread clamping members relatively constructed to separate said thread clamping members near the end of the take-up stroke of said take-up member.

25. In a sewing machine, the combination 55 of a stitch setting take-up member having a thread engaging part, a thread tension separate from said take-up member, means for operating said take-up member to cause 60 said take-up member to take up and set the stitch, and means operating through said take-up member to actuate said thread tension near the end of the take-up stroke of said take-up member to relieve the tension 65 on the thread.

26. In a sewing machine, the combination 70 of a stitch setting take-up lever having a thread engaging part, a thread tension, and a lug on said take-up lever adapted to engage and actuate said tension near the end of the take-up stroke of said take-up member to relieve the tension on the thread.

In testimony whereof we affix our signatures in presence of two witnesses.
